UNITED STATES PATENT OFFICE.

JAMES M. THAYER, OF RANDOLPH, MASSACHUSETTS.

CAR-HEATER.

SPECIFICATION forming part of Letters Patent No. 361,469, dated April 19, 1867.

Application filed March 1, 1886. Serial No. 193,570. (No model.)

To all whom it may concern:

Be it known that I, JAMES M. THAYER, of Randolph, county of Norfolk, and State of Massachusetts, have invented an Improvement in 5 Car-Heaters, of which the following description, in connection with the accompanying drawings, is a specification, like letters on the drawings representing like parts.

This invention has for its object to construct 10 a simple and efficient car-heater, especially adapted for heating horse-cars.

In accordance with this invention a heater of peculiar construction is employed, the boiler of which is connected by circulation-pipes 15 with two or more reservoirs or tanks, the latter also being connected together by pipes, so as to insure a continuous circulation.

Figure 1 shows in vertical section a heater embodying this invention; Fig. 2, a cross section of the heater, taken on the dotted line $x-x$; Fig. 3, a top view of the heater; Figs. 4 and 5, plan and side views of the heater, tanks or reservoirs, and the circulation-pipes.

The reservoir or tank A, of sufficient size 25 and dimensions to contain an abundant supply of oil, is provided in this instance with four burners, (shown as ordinary wick-tubes, a,) having toothed wheels rotated by thumb-nuts a', for moving the wick, and also having the 30 slotted crown a''. A suitable gauze plate, a'', surrounds the burners to permit an inlet of air. The reservoir or tank A is supplied with several division-walls, A', open at their lower ends to permit the oil contained within the 35 tank to seek the same level, the said division-walls serving to prevent splashing of the oil as the car is jolted along the track.

The supply-pipe A², provided with the cap A³, is attached to one side of the reservoir A, 40 that the same may be fed when necessary, and a suitable float, 50, rests upon the surface of the oil contained within the reservoir A, its stem 52 passing upward and out of a tube, 53, of any desired length, to thus indicate the supply of oil contained within the reservoir A.

Elongated combustion-chambers b are provided—one for each burner—and suitable outlet passages or tubes, b' b'', lead from the top portion of the said combustion-chambers b and 45 enter the hot-air chamber c, each combustion-chamber in this instance being provided with two such outlet passages or tubes extending

from opposite sides thereof; yet it is obvious that the said outlet tubes may be variously arranged—as, for instance, one tube connecting 55 all the combustion-chambers and leading into the hot-air chamber may be employed and the same result obtained, the only necessity being to supply the combustion chambers with outlets which shall enter the hot-air chamber c. 60

The combustion-chambers b are all located within the boiler d, containing water, the outlet tubes b' b'' of the said combustion-chambers passing through the walls of the said boiler, which latter is preferably of a dome shape, to 65 maintain a perfect circulation of the water and reduce the friction.

The interior top portion of the boiler d is composed of two oppositely-curved walls or surfaces, 12 12, the meeting edges of such 70 curved surfaces forming one of the diameters of the top portion of the boiler, while the opposite edges terminate at the circumference thereof, thus forming a distinct dome-shaped compartment for each outlet-pipe d' d''. 75

The hot-air chamber c, into which the outlet-tubes of the combustion-chamber lead, thus forms a jacket for the boiler d, both the boiler and hot-air chamber preferably being circular in cross section.

The flue c' (see dotted line, Fig. 1, and full lines, Figs. 2 and 3) leads from the top portion of the hot-air chamber c, opposite the means employed for moving the wicks, to thereby maintain a free circulation of air within 85 the said chamber, the said flue thence passing upward and out of the car.

The heater is herein shown as located at an intermediate point along one side of the car; but it is obvious that the same may be located 90 at any other convenient place either within or below the car.

The boiler d is provided at or near its top portion with outlet pipes or passages d' d'', which enter the top portions of the tanks or 95 reservoirs e e', of rectangular or other shape, and located on either side of the heater, while return-pipes d' d'' lead from the bottom of said tanks and enter the boiler d at its lower end. The pipe f also leads from the top portion of 100 the boiler d, extending transversely across the car and connected by a T-connection with the pipe f', which enters the top portions of two tanks or reservoirs, g g', of a construction simi-

lar to the tanks $e e'$, and located upon the opposite side of the car. The return-pipe f^2 , parallel with the pipe f' , but entering the boiler at its lower end, is connected by a T-connection with the pipe f^3 , entering the said tanks $g g'$ at their lower ends.

At the extreme lower ends of the tanks $e g$ suitable elbow-pipes, $h h'$, join an upright pipe, h^3 , which latter enters the small reservoir h^3 , located at the top of the car, and from the top portions of each of the tanks $e e' g g'$, adjacent to the heater, upright pipes $i i' i^2 i^3$ lead, all of which latter are joined to the main pipe m by suitable connecting-pipes, $m' m^2 m^3 m^4$, the said main pipe m also entering the small reservoir h^3 . The small reservoir h^3 is provided with an opening, 10, through which the said reservoir is supplied with water, to thus serve as a supply-reservoir or fountain-head for the entire apparatus. The supply-reservoir h^3 is kept but partially filled, to permit the water to expand. An outlet or vent, $n n'$, leads from the union of the pipes $m' m^2 m^3 m^4$ opposite to the main pipe m , and terminates beneath the car.

The unions employed in connecting the pipes are of any suitable design well known to steam-fitters.

The heating medium employed being hot water, a continuous circulation is kept up within the tanks $e e' g g'$ by the outlet and return pipes from the boiler d ; or should the temperature of the water rise sufficiently, the pipes $i i' i^2 i^3$, their connecting pipes $m' m^2 m^3 m^4$, the main pipe m , reservoir h^3 , and the pipes $h^2 h' h$ serve to maintain a free circulation and thereby prevent explosion, the pipe n being employed in excessive temperatures.

It will be seen that by the construction of the heater and by the arrangement of tanks and pipes as herein described the heat is thoroughly and evenly distributed throughout the car, and the expense attending the use of the apparatus will be very small.

The apparatus herein described is applicable to many other well-known purposes besides heating horse-cars.

If desired, any suitable number of combustion-chambers may be employed, one for each burner, or one combustion-chamber may be constructed to contain two or more burners, 50 without departing from this invention.

If desired, the tanks or reservoirs, which serve as radiators, may be heated with steam instead of water; but as such construction would add to the expense of the heater, it may 55 not be deemed expedient.

I claim—

1. A heater composed of an oil-reservoir, one or more burners attached to the same, a boiler within which said burners are inclosed, 60 and a hot-air chamber surrounding the boiler and in communication with the burners, combined with two or more tanks or reservoirs connected with the boiler by inlet and return pipes and a supply-tank, substantially as described.

2. The boiler d , having the two oppositely-curved walls 12 and 12, the meeting edges of which are diametrical with respect to the boiler and extend thence in two arches to the circumference to make two chambers, combined with the outlet-pipes for said chambers, and a heating apparatus arranged within said boiler, substantially as described.

3. In a heater, the boiler d , its outlet and return pipes, and two or more tanks or reservoirs into which the said outlet and return pipes from the boiler lead, combined with the supply-tank h^3 , and pipes for connecting the same with the tanks or reservoirs, whereby a 80 continuous circulation is maintained at high temperature, substantially as described.

In testimony whereof I have signed my name to this specification in the presence of two subscribing witnesses.

JAMES M. THAYER.
